Charles J. Shepard, of Brooklyn, N.Y.
Letters Patent No. 869 - Dated Feb 10th 1857

Dec. 8th 9

The Schedule referred to in these Letters Patent and making part of the same.

To all to whom these Presents may come.

Be it known that I, Charles J. Shepard of Brooklyn in the County of Kings and State of New York, have invented, made or produced a new and original ornamental design for the fronts of Cooking ranges. And I do hereby declare that the following description and annexed drawing fully set forth and illustrate the same.

In the drawing Fig. 1 is an elevation of the front plate of a range, shewing the ornaments on the centre and one side of the range, the other side being only shewn in outline as the same ornaments are to be applied thereto as on the left side.

Fig. 2. is a plan of the curved unornamented edge of the top plate.

The edges of the front plate and also around the doors are to be ornamented with ranges of egg shaped corrugations or knobs, and ornamental panels are formed on the projecting mullature on the upper part of the plate, and somewhat similar ornamented panels are placed below and at the outer sides of oven doors. and over said ornamental panels to the right and left of the oven door is a female face inclosed in drapery surmounted by a double scroll or capital as represented.

The oven doors are ornamented in the centre with a circle or wreath enclosing a series of arcs of circles around a centre flower as represented.

The centre or fire door has an ornamental panel containing the name, as shown and the ash pit cover and register below is ornamented as repre-

resented.

Having thus set forth and shewn the ornamental design of my range front.

What I claim and desire to secure by Letters Patent, is

The ornamental design of the front plate door and edge of the top plate as described and represented in the drawing.

In witness whereof I have hereunto set my signature this Thirtieth day of December 1856.
